UNITED STATES PATENT OFFICE

2,335,334

APPARATUS FOR OPERATING ON SHEET MATERIAL

Carl M. Yoder, Lakewood, Ohio

Original application April 15, 1935, Serial No. 16,373. Divided and this application November 6, 1939, Serial No. 303,037

13 Claims. (Cl. 80—3)

This invention relates to apparatus for operating on sheet metal stock, that is hot or cold rolled, of varying width, thickness and length and fed continuously through the apparatus.

This application is a division of my application Serial No. 16,373, filed April 15, 1935, now Letters Patent No. 2,179,461, dated November 7, 1939.

One object of the invention is to provide an improved apparatus for trimming and finishing the side edge of sheet material ready for subsequent treatment.

Another object of the invention is to provide an improved apparatus for simultaneously conditioning or finishing the opposite side edges of a plurality of sheet metal sections or strips.

Another object of the invention is to provide an improved apparatus for cutting sheet metal stock into sections and simultaneously conditioning or finishing the side edges of the sections.

A further object of the invention is to provide an improved apparatus capable of handling sheet stock, which is cold or hot rolled and of maximum width, cutting it into strips of a predetermined width and finishing the strips ready for subsequent manipulation or treatment and simultaneously coiling the strips to permit the handling or transportation of the material for any desired purpose.

Other objects of the invention will be apparent to those skilled in the art to which my invention relates from the following description taken in connection with the accompanying drawings, wherein

Figs. 1 and 2 together show a side elevation of an apparatus embodying my invention, parts being broken away.

Figs. 3, 4 and 5, together show a plan view of the apparatus.

Fig. 6 is a section on the line 6—6 of Fig. 4.

Fig. 7 is an elevation of that portion of the apparatus supporting the processing, cutting or slitting and scrap cutting mechanisms from the side of the apparatus remote from the side shown in Fig. 1.

Fig. 8 is a section on the line 8—8 of Fig. 3.

Fig. 9 is a fragmentary section on the line 9—9 of Fig. 1.

Figs. 10 and 11 are enlarged fragmentary sectional views substantially on the line 10—10 of Fig. 3; the former figure showing the cutter devices in cutting position or relation and the latter figure showing these devices adjusted to an in-operative position.

Figs. 12 and 13 are views of the parts shown in Figs. 10 and 11, respectively.

Fig. 14 is a fragmentary section on the line 14—14 of Fig. 1.

Fig. 15 is an elevation of that portion of the apparatus supporting the edge conditioning or finishing mechanism from the side of the apparatus remote from the side shown in Fig. 2; on the line 15—15 of Fig. 4.

Fig. 16 is an end elevation of the mechanism shown in Figs. 2 and 4 looking toward the left; being a view on the line 16—16 of Fig. 2, but with the material omitted.

Fig. 17 is a section on the line 17—17 of Figs. 2 and 6.

Fig. 18 is a section on the line 18—18 of Fig. 5.

Fig. 19 is a diagrammatic view; this view also illustrating a modified arrangement in which the sections are cut transversely into lengths instead of being coiled.

Fig. 20 is a fragmentary view, enlarged, showing the engagement of one finishing or edging device with one side edge of a cut section.

Fig. 21 is a fragmentary view similar to Fig. 20, but showing a different form of construction.

Fig. 22 is a side elevation showing a modified construction of the mechanism for conditioning or finishing the edges of the sections.

Fig. 23 is an elevation of the mechanism shown in Fig. 22 from the opposite side thereof.

Fig. 24 is a plan view of the parts shown in Figs. 22 and 23.

Fig. 25 is a section on the line 25—25 of Fig. 22.

The disclosed apparatus comprises a plurality of mechanisms correlated to uncoil the sheet metal material as it comes from the mill, to level or straighten the material, trim either or both edges of the material, finish the side edges of the material, cut the material longitudinally into sections each of a predetermined width, finish the opposite edges of each section and finally cut the section or sections into lengths or re-coil them ready for handling or transportation. Referring to the drawings, 2 indicates as an entirety the mechanism for leveling or straightening the material, 3 indicates as an entirety the mechanism for trimming either or both side edges of the material and/or cutting it longitudinally into sections. 4 indicates as an entirety the mechanism for conditioning, finishing or rounding the opposite edges of the material or sections thereof, 5 indicates as an entirety the mechanism for re-coiling the material or the sections thereof, in the event the material or the sections thereof are not cut into lengths, as shown in Fig. 19, and 6

indicates a mechanism for cutting the trimmed-off portions or scrap into lengths or pieces. As the apparatus shown is intended to operate on sheet metal that is relatively thick and of varying lengths, these mechanisms are mounted on separate bases or frames for convenience in manufacturing and setting. The apparatus may be constructed to accommodate sheet material of maximum width.

The material A is supplied to the leveling mechanism 2 from a coil which is supported in any desired manner.

The leveling mechanism comprises the front feed rolls 9a, rear feed or delivery rolls 26, which feed the material to guides 3a of the trimming and cutting mechanism 3, and related intermediate upper and lower rolls 21, 28, any number of which may be provided. The peripheries of the rolls 21, 28, are spaced less than the thickness of the material and when desired they may intersect a plane lying midway between their axes, the purpose being to flex or bend the material in opposite directions on transverse lines, during feeding of the material, to level it, so as to remove therefrom wrinkles, distorted portions and unequal stresses in the metal, whereby the material may be accurately manipulated and shaped or re-shaped by dies or other apparatus for various purposes and uses. In the construction shown for purposes of illustration the lower rolls 9a, 26 and 28 are mounted in fixed bearings provided in standards 29, which are mounted on a suitable support 30, whereas the upper rolls 9a, 26 and 27 are independently adjustable vertically dependent upon the thickness of the material. Each upper roll is mounted in a pair of journal boxes 31 slidably fitting the walls of openings formed in the standards 29, these boxes being preferably connected to the lower ends of screws 32, which are arranged to rotate relative to the boxes. The upper ends of the screws are threaded through openings formed in bridge members 33, so that by rotating the screws the boxes may be raised or lowered. The bridge members 33 are suitably secured to the standards 29. By preference, all of the rolls 9a, 28, 27 and 26 are positively driven. For this purpose these rolls have at one side, extended ends carrying gears enclosed in a casing 34 (see Figs. 3 and 7), the casing being secured to the adjacent standard in any desired manner. 35 indicates a gear preferably driven by a driven gear 36 of the driving means for the mechanism 3. The gear 35 meshes with a gear 37 fixed to the shaft of the lower roll 26; the gear 37 in turn meshes with a gear 38 fixed to the shaft of the upper roll 26. The gear 37 also meshes with and drives an idler 39, which is fixed to a shaft 40 mounted in the outer wall of the casing 34. The shaft 40 carries a gear (not shown) which is in mesh with a gear fixed to the shaft of the adjacent roll 28 to drive the latter and which meshes with a gear 42 fixed to the shaft of one of the rolls 21 (right hand roll 21 as viewed in Fig. 1) to drive it. The shaft for the roll 28 carries a second gear 43 (see dotted lines in Fig. 7) in a plane outwardly of the gears 38 and 42, the second gear 43 meshing with a gear 44 fixed to the shaft of the other roll 21. The gear 43 also meshes with an idler 45 which in turn meshes with a gear 46 fixed to the shaft of the other roll 28. The gear 46 operates through an idler 47 to drive a gear 48 fixed to the shaft of the lower roll 9a, the gear 48 meshing with a gear 49 fixed to the shaft of the upper roll 9a. As shown and above described, all of the

rolls 9a, 26, 27 and 28 are driven and have the same peripheral speed.

Referring to the mechanism 3 for trimming either or both edges of the material and/or cutting the material into longitudinal sections of any predetermined width: 50, 51, indicate a pair of standards, the former being mounted on the flooring or a suitable bed and the latter being mounted for adjustment transversely to the direction of feed of the material A, as later set forth. The standards 50, 51, support the opposite ends of upper and lower shafts 52, 53, by means of pairs of suitable journal boxes 54. As shown in Figs. 1, 7 and 8, the boxes have grooved side walls which slidably fit the sides of openings 54a formed in the standards, the boxes 54 for the shaft 53 preferably resting on the bottoms of the openings 54a and the boxes 54 for the shaft 52 being adjustably supported by bridge members 55 bridging the openings 54a and removably fixed to the upper ends of the standards 50, 51, by bolts 55a. The adjusting devices for each upper journal box comprise the following: 56 indicates an inverted cup-shaped member (see Fig. 9) suitably secured to the top of the adjacent box 54 for the upper shaft 52 and formed in its top wall with an opening. 57 indicates a screw having a head rotatably fitting the member 56, the shank of the screw extending loosely through the opening and its upper end portion being threaded into an opening 58 formed in the adjacent bridge member 55, whereby the screw is supported by the bridge member 55 and adjustable endwise when rotated to raise or lower the adjacent journal box. The free end of the screw shank is keyed to but slidably fits into a worm gear 59. The bridge member 55 is shaped to co-operate with a casting 60 to form a gear box for the worm gear and a worm (not shown) for driving the worm gear, the worm being fixed to a shaft 62 which carries the worm for the worm gear for adjusting the other box 56. Each bridge member 55, interiorly of the gear box, is formed with an annular wall 63 with which the adjacent gear engages. The walls of each bridge member 55 and the adjacent casting 60 are provided with thickened related walls 60a, which form bearings for the shaft 62. The shaft 62 carries an operating device, preferably a hand wheel 64, at one end, whereby the shaft may be rotated. If the shaft 62 is rotated, the worms fixed thereto will be driven and they in turn will rotate the worm gears 58; the latter in turn will rotate the screws 57, which, having threaded engagement with the walls of the openings, will raise the adjacent boxes 54 or permit them to gravitate downwardly (the slidable but non-rotatable connections between the gears and upper ends of the screws 57 permitting of either operation), whereby the shaft 52 will be adjusted relative to the shaft 53 to properly correlate the active edges of the cutting devices, as hereinafter set forth. The shaft 62 may be formed in sections, the adjoining ends of which are connected by clamping devices 61. At the ends of the shafts 52, 53, sets of devices 64 are provided for trimming the longitudinal side edges of the material to a predetermined width and intermediate the ends of the shafts 52, 53, I provide a set of slitting or cutting devices 65 to cut the material into sections a, a, of equal or predetermined unequal widths. As the standard 51 is adjustable the adjacent set of trimming devices 64 are preferably mounted for adjustment therewith. The trimming devices at the opposite ends of the standards may be similarly mounted; for

example, as shown in my copending application, Serial No. 12,818, filed March 25, 1935 (now Letters Patent No. 2,160,999, dated June 6, 1939). For this purpose the shafts 52, 53, slidably fit into and are keyed to sleeves 66 (Fig. 9) to rotate the latter. Each sleeve is provided at its inner end with a collar 67 to which the adjacent trimming device 64 is removably secured by bolts 64a. Between the sleeve 66 and the adjacent box 54 is provided suitable anti-friction bearing elements of a type to take end thrusts, the races carried by the sleeve being held in fixed relation by spacing elements and a nut 68 threaded on the outer end of the sleeve. Each trimming device 64 may be of sectional construction to facilitate assembly and replacement.

No claim is made herein to the mounting of the trimming devices, the assembly of such mounting with the journal boxes and adjustment of these parts with the adjacent standard as that forms in part the subject-matter of the aforesaid application.

The slitting devices 65 are mounted for adjustment axially of the shafts and for movement into and out of operative relation. Referring particularly to Figs. 10, 11, 12 and 13, 69 indicates a sleeve member slidably fitting each shaft 52, 53. The sleeve member 69 is provided with one or more threaded openings for suitable screws 69' arranged to project into and engage the bottom wall of the keyway formed in the adjacent shaft to lock the member 69, in its adjusted position. The outer wall of the member 69 is formed with annular grooves forming races for balls 70. 71 indicates an annulus formed on its inner wall with races concentric to the adjacent shaft and rotatable on the balls 70. The outer wall of the annulus 71 is formed with races 72 for balls 73, which races are eccentric to the shaft axis. 74 indicates a ring forming a support for the adjacent slitting device 65, the inner wall of the ring 74 being formed with races to engage the balls 73 and permitting the ring and its slitting device to freely rotate around the annulus 71. The annuli 71 are arranged, when in one position, to support the slitting devices in operative relation, as shown in Figs. 10 and 12, for slitting the material A longitudinally as the material moves between them; but, by reason of the eccentricity of the races 72, when the annuli are rotated a half revolution, the devices 65 will be moved away from each other, as shown in Figs. 11 and 13. Each annulus 71 is formed of two ring-shaped members, suitably bolted together (see Fig. 12) to permit of assembly. Each annulus 71 may be locked in either position. For this purpose each annulus is provided with an arm 75, notched at its outer end to removably receive a locking device 76 when in either position. Each locking device comprises a rod slidably supported at its opposite ends in horizontal guides 77 provided on the inner walls of the standards 50, 51. Each rod 76 may be held in the notch of the adjacent arm 75 by a set screw 78. A gear 36 is fixed to the shaft 53, and meshes with a gear 36a fixed to the shaft 52 to drive the latter. The shaft 53 is connected through a coupling 78 to a shaft 79 having a gear 80. The gear 80 meshes with a pinion 81 on a countershaft 82 which is provided with a worm gear 83. The gear 83 meshes with a worm fixed to a shaft 84, which is driven by a motor 85.

To permit of adjustment of the standard 51, I provide a pair of spaced sills 86 provided in a

pit C and having oppositely inclined walls forming ways for grooves 87 formed in the lower end of the standard 51. The sills 86 are formed with longitudinal T slots for bolts 88 by means of which the standard may be adjustably secured to the sills. 89 indicates a threaded opening formed in the standard 51 and arranged to receive a feed screw 90, which, when rotated and upon loosening of the bolts 88, serves to move or adjust the standard along the sills 86. The outer end of the screw is preferably power driven, such end being mounted in the side walls of a casing 91 and fixed to a worm gear 92 disposed between said side walls, the gear in turn meshing with a worm fixed to a shaft 93, which is driven by a motor 94.

As the material A moves to and through the trimming and slitting mechanism 3, its marginal edges are trimmed off by the devices 64 and cut or slit longitudinally by the devices 65. As only one set of slitting devices are shown, the material A may be cut into two sections of equal or unequal width, depending upon the transverse adjustment of the devices 65; but more than one set of devices 65 may be provided when desired. By positioning the devices 65 in an in-operative position, the slitting operation may be omitted as the material feeds forwardly. As the trimming and slitting devices are mounted on the same shafts, these operations are effected simultaneously but this arrangement is not an essential feature of my invention. The trimmed-off marginal edges are directed downwardly to the scrap cutting mechanism 6, which is shown diagrammatically and preferably is similar to that shown in my aforesaid co-pending application. No claim is made to this mechanism or to it in combination with a trimming mechanism as that forms in part the subject-matter of said co-pending application. The scrap or trimmed-off material is cut into suitable lengths and gravitates into a receiver D (see Fig. 1).

From the trimming devices 64 and slitting devices 65, the material A is guided by and between pairs of guide members 3a' to a set of feed rolls 95, which are preferably driven in the following manner through a gear train within a casing 34a, certain of the gears serving to rotate the scrap cutters 96, 96' of the mechanism 6: 97 indicates a gear in mesh with the gear 36 (see Fig. 7). The gear 97 meshes with a gear 98 fixed to the shaft for the scrap cutter 96. The gear 98 meshes with a gear 99 fixed to the shaft of the scrap cutter 96'. The gear 99 through idlers 100 and 101 drives a gear 102 fixed to the shaft of the lower feed roll 95 and the gear 102 meshes with a gear 102' fixed to the shaft of the upper feed roll 95.

From the feed rolls 95 the sections a pass to the edge conditioning or finishing mechanism 4 having a plurality of sets of devices, one set for each section a, two sets being herein shown and indicated at 103, 103a. As the sections a are in edge to edge relation when slit, the sets of devices 103, 103a, are so arranged that they may condition, finish or round the side edges of both sections simultaneously, while providing for the continuous feed of the sections to a mechanism for cutting them into uniform lengths, as shown diagrammatically in Fig. 19 or to a mechanism for simultaneously coiling the sections, as shown in Figs. 2, 5 and 18. In this arrangement, one section is guided out of the plane in which the other section feeds or moves, but by preference both sections are guided to and fed in spaced planes above and below the plane in which the

material moves through the leveling mechanism 2 and trimming and slitting mechanism 3, and the sets of edging devices are in these spaced planes, respectively. The sets of devices 103, 103a, are positioned in different horizontal planes and spaced longitudinally of the material as shown in Figs. 2, 4 and 6 or in the same transverse plane as shown in Figs. 22, 23, 24 and 25.

Referring to Figs. 2, 4, 6, 16 and 17, 104 indicates standards suitably mounted on a base 104a. 106 indicates a U-beam having end walls suitably secured to the standards 104. 107, 107, indicate a pair of supports provided on their opposite sides with lugs removably and adjustably secured to the sides of the beam 106, for supporting one set of finishing or edging devices (set 103). Each support is formed with an opening 108 and its upper and lower walls are formed with aligned openings to support a vertical shaft on which an edging device 103b freely rotates. The device 103b comprises a roller formed with a groove shaped to receive the adjacent marginal edge of the section, the bottom of the groove engaging the lateral surface of the edge and the sides of the groove engaging the opposite faces of the section. The edging devices 103b are in opposed co-acting relation so as to engage the opposite sides edges of the section in the same transverse plane. Each section *a* as it leaves the trimming and slitting devices is rough and provided with burs, so that by passing the section to and between a pair of edging devices the metal of the edges is finished, smoothed, conditioned or rounded as may be desired, to eliminate the roughness and burs and condition them for welding or other purposes. As shown in Fig. 20, the edges of the section may be finished to be disposed at right angles to the surfaces thereof or, as shown in Fig. 21, these edges may be rounded. By preference, I associate with the edging devices a pair of holders 110 which engage the upper and lower surfaces of the section to prevent distortion or buckling of the section while being engaged by the edging devices. In the form of construction shown in these views, the holders comprise a pair of freely rotatable rolls 110. The axes of the rolls 110 are disposed in the plane cutting the axes of the edging devices 103b. The rolls 110 are provided at their opposite ends with stud shafts which loosely rotate in bearings provided in the upper and lower walls of the supports 107. 111, 112, indicate pairs of driven feed rolls disposed forward and rearward of the set of edging devices 103 and serving to guide and feed the section in the plane of the grooves in the devices 103b. From the feed rolls 112 the section *a* passes to and between a pair of guide rolls 113 suitably mounted at the rear ends of the standards 104 and from the latter rolls the section may lead to the coiling mechanism 5.

The feed rolls 111, 112, of each pair are preferably mounted similarly to the feed rolls 8a and 26, but are driven in the following manner: 114 indicates a worm gear in mesh with a worm fixed to the shaft 84. The worm gear 114 is fixed to a shaft 115 carrying a pinion 115a which is in mesh with a gear 116, the gear in turn being fixed to a shaft 116a (see Fig. 4). The shaft 116a is connected through a coupling 117 to one end of the shaft of a guide and feed roll 118 to which reference will later be made. The opposite end of the shaft for the roll 118 carries a gear 119 (Fig. 15) which meshes with a gear 120 fixed to the upper feed roll 111. The gear 120 meshes

with a gear 120a fixed to the shaft for the lower feed roll 111 and the latter gear, through an idler 121 drives a gear 122 fixed to the shaft for the lower feed roll 112. The gear 122 meshes with a gear 122a fixed to the shaft for the upper feed roll 112.

The other section *a* of the material is guided and fed by the roll 118 (already referred to) and a plate 123 to the set of edging devices 103a. The plate 123 is mounted on a cross bar 123a secured at its ends to the standards 104. The set of devices 103a is arranged in a plane above the set 103 and spaced longitudinally of the direction of feed of the material, but in alignment with the adjacent section *a*. The set of devices 103a comprise opposite related edging devices constructed and mounted similarly to the set of devices 103 already referred to, to engage the opposite edges of the section and have associated with them holders 110' which engage the adjacent section *a* in line with the edging devices, these rolls being constructed and mounted in the same manner as the rolls 110. 111', 112', indicate pairs of feed rolls disposed forward and rearward of the set of devices 103a. The feed rolls 111', 112', are mounted similarly to the rolls 111, 112, and are driven as follows (see Fig. 15): 124 indicates a gear fixed to the shaft for the lower feed roll 111' and in mesh with and driven by the gear 122a. The gear 124 also meshes with a gear 124a fixed to the shaft for the upper feed roll 111' and with an idler 125. The idler 125 meshes with a gear 126 fixed to the shaft for the lower feed roll 112' and the gear 126 in turn meshes with a gear 126a fixed to the shaft for the upper feed roll 112'. The gears above referred to are enclosed in a suitable casing 127 (see Fig. 4).

Figs. 22 to 25, inclusive, show a modified form of construction in which the sets of edge finishing devices, the adjacent aligned rolls and the front and rear feed rolls for each set are disposed in the same transverse plane but spaced in different horizontal planes in alignment with the sections *a*, respectively. In this form of construction the standards may be formed in sections 104x, 104x' (see Figs. 23 and 25). The upper set of edge finishing devices 103x and the aligned rolls and the front and rear feed rolls are similar to like parts already described and the corresponding parts of the lower set 103x' and the parts associated therewith are also similar to those already referred to, except that the upper feed rolls 111x, 112x, are not adjustably mounted, whereas the lower feed rolls 111x, 112x are adjustable vertically. The journal boxes for the upper rolls 111x, 112x, fit into openings 128 and rest on lugs 128' fixed to the outer walls of the standards and are held thereon by lugs 128a fixed to and depending from the flange 128b of the upper standards 104x' which is suitably bolted to the lower standards 104x. The journal boxes for the shafts of these lower feed rolls slidably fit the openings 128 in the standard sections 104x and engage wedges 129' which are operable in ways at the lower ends of the openings and when moved endwise raise or lower the adjacent journal boxes. Each wedge 129' is constructed to rotatably but non-slidably support a shaft 129, shaped at its outer end to take a suitable tool to effect a rotation of the shaft and provided at its inner end with threads and engaging a threaded opening formed in the adjacent standard section, whereby rotation of the shaft 129 will effect movement of the wedge in

either direction. In this form of construction, the shafts for each pair of feed rolls are drivingly connected by gears 130, 131, respectively (see Fig. 23). The gears 131 connected to the shafts for the lower feed rolls related to the upper edge up-setting devices are in mesh with and driven by an idler 132 which is driven by a gear 133. The gear 133 is in mesh with and drives the gears 130 connected to the shafts for the upper feed rolls related to the lower edge up-setting devices. The gear 133 is fixed to a drive shaft 134. The shaft 134 may be connected to the driven shaft 84 as already set forth in connection with the shaft 116a or driven by a separate motor.

The re-coiling mechanism 5 comprises the following: 135 indicates a pair of spaced standards mounted on a support or base 135a. 136, 137, 138, indicate a set of driven rolls between which the sections *a*, *a*, feed in side by side relation (see Fig. 5), these rolls being so arranged that they co-operate to bend or curve the sections as this feeding takes place. The shafts for these rolls are suitably mounted in journal boxes mounted in the standards, the boxes for the shafts of the rolls 137, 138, respectively, being adjustable to insure the desired curvature, so that the sections, will readily wind into coils A', as shown. 139 indicates a bed mounted on the base 135a forward of the standards 135. At its opposite ends the bed is formed with up-standing lugs 140 having openings to receive and support a rod or shaft 141, on which is pivoted a shelf 142. The shaft 141 supports a roller 143 which co-operates with a roller 144 suitably mounted on the outer end of the shelf 142, to support the coils A'. As the rollers 143, 144, are free to rotate, they permit each coil to rotate about its axis due to the feed of the section *a* from the rolls 136, 137, 138. The shelf 142 is supported at its outer end by a pair of screws 145 threaded through openings formed in the walls of the bed 139. The screws 145 are provided with hand wheels 146 for rotating them to swing the shelf upwardly to a desired position to accommodate the coil when the first convolution thereof is produced. As the coil A' increases in diameter, due to the progressive coiling action, the shelf 142 may be adjusted downwardly to compensate for such increase. The shafts for the rolls 136, 137, 138, are driven through suitable gearing in a casing 147 by a shaft 148, the shaft being driven through reducing gears 149 by a shaft 150, which in turn is driven through a worm and worm gear by the shaft 151 of a motor 152.

It will be understood that the driven elements of each mechanism have the same peripheral speed and that these elements of all the mechanisms are driven at speeds which insures a uniform feed of the material to prevent slack or buckling thereof while passing from one mechanism to the other.

To those skilled in the art to which my invention relates, many changes in construction and widely differing embodiments and applications of the invention will suggest themselves without departing from the spirit and scope of the invention. My disclosures and the description herein are purely illustrative and not intended to be in any sense limiting.

What I claim is:

1. In apparatus of the class described, the combination with supporting means and means for supplying sheet material, of a pair of stand-

ards on said supporting means, shafts mounted on said standards, cutting devices on said shafts for slitting the sheet material longitudinally into sections, and sets of devices for simultaneously finishing the opposite side edges of the sections, disposed in different horizontal planes and in alinement therewith, respectively.

2. In apparatus of the class described, the combination with supporting means and means for supplying sheet material, of a pair of standards on said supporting means, shafts mounted on said standards, cutting devices on said shafts for slitting the sheet material longitudinally into sections, sets of devices for simultaneously finishing the opposite side edges of the sections, disposed in different horizontal planes and in alinement therewith, respectively, and a pair of holders in a plane cutting the axes of the devices of each set and engaging the upper and lower surfaces of the adjacent section.

3. In apparatus of the class described, the combination with supporting means and means for supplying sheet material, of a pair of standards on said supporting means, shafts mounted on said standards, cutting devices on said shafts for slitting the sheet material longitudinally into sections, sets of devices for simultaneously finishing the opposite side edges of the sections, disposed in different horizontal planes and in alinement therewith, respectively, and a pair of driven rolls disposed adjacent to each of said sets of devices for feeding the material relative thereto.

4. In apparatus of the class described, the combination with supporting means and means for supplying sheet material, of a pair of standards on said supporting means, shafts mounted on said standards, cutting devices on said shafts for slitting the sheet material longitudinally into sections, sets of devices for simultaneously finishing the opposite side edges of the sections, disposed in different horizontal planes and in alinement therewith, respectively, a pair of holders in a plane cutting the axes of the devices of each set thereof and engaging the upper and lower surfaces of the adjacent section of material, and a pair of driven rolls disposed adjacent to each of said sets of devices for feeding the material relative thereto.

5. In apparatus of the class described, the combination with supporting means and means for supplying sheet material, of a pair of standards on said supporting means, shafts mounted on said standards, means for trimming the marginal side edges of the material, devices on said shafts for slitting the sheet material longitudinally into sections, and sets of devices for simultaneously finishing the opposite side edges of the sections, disposed in different horizontal planes and in alinement therewith, respectively.

6. In apparatus as claimed in claim 1, wherein one of said sets of devices is arranged in advance of the other set of devices.

7. In apparatus of the class described, the combination with supporting means and means for supplying sheet material, of a pair of standards on said supporting means, shafts mounted on said standards, cutting devices on said shafts for slitting the sheet material longitudinally into sections, sets of devices for simultaneously finishing the side edges of the sections, disposed in different horizontal planes and in alinement therewith, and means for coiling the sections.

8. In apparatus of the class described, the combination with supporting means and means for

supplying sheet material of a pair of standards on said supporting means, shafts on said standards, sets of devices on said shafts for trimming the marginal side edges of the material, a set of cutting devices on said shafts between said sets of trimming devices for cutting the material longitudinally into sections, and pairs of rolls disposed in different horizontal planes and in alignment with the sections, respectively, for simultaneously finishing the opposite side edges thereof.

9. In apparatus of the class described, the combination with supporting means and means for supplying sheet material, of a pair of standards on said supporting means, shafts mounted on said standards, cutting devices on said shafts for slitting the sheet material longitudinally into sections, and sets of devices for simultaneously finishing the opposite side edges of the sections, respectively disposed in different horizontal planes with their axes in the same transverse plane.

10. In apparatus of the class described, the combination with a support and means for supplying sheet material, of spaced supporting means on said support, cutting devices mounted on and between said supporting means for slitting the material longitudinally into sections during feeding thereof, transversely arranged beams, each supported at its opposite ends on said supporting means, said beams being supported one above the other but spaced longitudinally of the direction of feed of the material, a pair of supporting devices spacedly mounted on each beam, and an edging device rotatably mounted on each supporting device arranged to co-act with the edging device mounted on the other supporting device to finish the side edges of one of the sections of the material.

11. In apparatus of the class described, the combination with a support and means for supplying sheet material, of spaced supporting means on said support, cutting devices mounted on and between said supporting means for slitting the material longitudinally into sections during feeding thereof, transversely arranged beams, each supported at its opposite ends on said supporting

means, said beams being supported one above the other but spaced longitudinally of the direction of feed of the material, a pair of supporting devices spacedly mounted on each beam, an edging device rotatably mounted in each supporting device arranged to co-act with the edging device mounted in the other supporting device to finish the side edges of one of the sections of the material and a pair of holders in a plane cutting the axes of each pair of edging devices mounted at their opposite ends in the adjacent supporting devices for said edging devices and engaging the upper and lower surfaces of the adjacent section.

12. In apparatus of the class described, the combination with a support and means for supplying sheet material, of spaced supporting means on said support, cutting devices mounted on and between said supporting means for slitting the material longitudinally into sections during feeding thereof, transversely arranged beams, each supported at its opposite ends on said supporting means, said beams being supported one above the other but spaced longitudinally of the direction of feed of the material, a pair of supporting devices spacedly mounted on each beam and each having spaced upper and lower walls, a shaft mounted at its opposite ends in said walls, and an edging device mounted on each of said shafts between the adjacent walls and arranged to co-act with the edging device mounted on the other shaft to finish the side edges of one of the sections of the material.

13. In apparatus of the class described, the combination with a support and means for supplying sheet material, of spaced supporting means on said support, cutting devices mounted on and between said supporting means for slitting the material longitudinally into sections during feeding thereof, and sets of devices for simultaneously finishing the opposite side edges of the sections, said sets of devices being supported on and between said spaced supporting means in different horizontal planes and in alignment with said sections, respectively.

CARL M. YODER.
